UNITED STATES PATENT OFFICE

MAURICE ETIENNE JULLIARD, OF PARIS, FRANCE

DESIGN FOR A RAZOR

Application filed August 19, 1931. Serial No. 40,884. Term of patent 3½ years.

To all whom it may concern:

Be it known that I, MAURICE ETIENNE JULLIARD, a citizen of the French Republic, residing at Paris, France, have invented a new, original, and ornamental Design for a Razor, of which the following is a specification, reference being had to the accompanying drawing, forming part thereof.

I claim:

The ornamental design for a razor as shown.

MAURICE ETIENNE JULLIARD.
